Application September 13, 1946, Serial No. 696,848

32 Claims. (Cl. 66—89)

1

The present invention relates to full-fashioned knitting machines and more particularly to a covering knife arrangement for the fashioning mechanism of such machines.

All full-fashioned knitting machines are provided with fashioning points for varying the width of the fabric being knitted. At times, it is desired to prevent certain of the fashioning points from engaging and transferring loops of the fabric and for this purpose, so-called covering "knives" are used. Such "knives" are used on footer machines in which the fashioning points are carried in pairs of wide and narrow combs for making the diamond point toe narrowings and are also a necessary part of single unit machines, machines for making both leg and foot portions of blanks for full-fashioned single unit stockings, when it is desired to shape the toe portion by diamond point narrowings. In the latter type machines difficulties have arisen which were not found in the footer machines. The knives on footers for making the diamond point toe narrowings are always at the centers of the knitting sections of the machines but operate only when reinforced fabric is being formed so that it is relatively unimportant if they touch the fabric in operating. In single unit machines, however, it has been found necessary to place the narrow combs in inactive position at the center of each knitting section while all fashioning operations in shaping the stocking blank, except those in the toe portion, are performed by the wide combs. Under these conditions, the narrow combs are also lowered at each fashioning operation and therefore the knives must be operated at each fashioning operation, prior to the diamond toe narrowings, to prevent the points of the narrow combs from acting on the loops. In the usual operation to prevent fashioning points from engaging loops the covering knives touch the fabric several times in each operating cycle which, as hereinbefore set forth, occurred in the reinforced toe portion, resulting in little or no damage to the fabric. In operating, in the knitting of single unit blanks, to prevent the points of the narrow combs from displacing the loops, the knives engage the unreinforced portion of the blank, which due to the fineness of the yarn often results in irreparable damage thereto.

Further, in a single unit machine fitted with an automatic welt turner of a certain type or of certain types, the ordinary center knives are found to strike the hooks in the welt bars because, after the welt has been turned, the welt

2

hooks are close to and in front of the line of the needles and remain engaged with the loops while certain narrowings are performed before the welt bars move far enough from the needle row to prevent the knives from striking the welt hooks. It has been found also desirable, when knitting certain yarns of which nylon is an example, because of the curling upwardly of the edge portions of the blank at the line of the turned welt, to allow the welt bars to lie on the rails rearwardly of their normal retracted position after their hooks have been disengaged from the loops. When in such position, and in the case where narrowings are then performed in the fabric, the old type center knife interferes with the hooks on the welt bar.

It is therefore an object of the invention to provide an arrangement for operating covering knives for full-fashioned knitting machines which will move the active edge of a covering knife in a predetermined path entirely removed from the fabric at all times.

Further, a certain type of single unit stocking which has achieved considerable popularity may be made conveniently by improved apparatus including a pair of covering knives for each section placed so as to act when in use at the selvages of certain heel sections of the blank.

Another object of the invention is to provide a novel means for operating both a center knife and a pair of selvage knives in a knitting section and with an improved action incident to its construction.

Still another object of the invention is to provide new and improved means for operating both a center knife and a pair of selvage knives in a knitting section from a single cam.

A further object of the invention is to provide a means in a multi-section knitting machine for operating both a central knife and a pair of selvage knives in each knitting section and in which the mechanism of one set of knives assists in positioning knives in the other set.

Another object of the invention is to provide a covering knife arrangement for full-fashioned single unit machines in which the covering knife will miss welt hooks which may lie in or on the fabric and close to the needle row.

With these and other objects in view, which will become apparent from the following detailed description of the illustrative and practical embodiment of the invention, shown in the accompanying drawings, the invention comprises the novel elements, features of construction and combination of parts in cooperative relationship, as

hereinafter more particularly pointed out in the claims.

In the drawings:

Figure 1 is a front elevational view of a portion of a full-fashioned knitting machine to which the invention has been applied, showing a portion of the narrowing machine with covering knives thereon and the cams for operating the narrowing machine and the knives;

Fig. 2 is a detailed view taken substantially on the line 2—2 of Fig. 1, looking in the direction of the arrows and on a slightly reduced scale relative to Fig. 1, and showing the portion of the narrowing machine operating mechanism;

Fig. 3 is a sectional view through a full-fashioned knitting machine taken substantially on the line 3—3 of Fig. 1, looking in the direction of the arrows;

Fig. 4 is a sectional detailed view taken substantially on the line 4—4 of Fig. 1 looking in the direction of the arrows and on an enlarged scale relative to Fig. 1;

Fig. 5 is a sectional view taken substantially on the line 5—5 of Fig. 1, looking in the direction of the arrows, showing the parts in the same relative positions as in Fig. 9;

Fig. 6 is a detailed front view of the right hand portion of Fig. 1, showing a portion of the operating means for the knives;

Fig. 7 is a detailed sectional view taken approximately on the line 7—7 of Fig. 6;

Fig. 8 is a detailed sectional view taken substantially along the line 8—8 of Fig. 6 as viewed in the direction of the arrows;

Fig. 9 is a detailed sectional view taken substantially on the line 9—9 of Fig. 6;

Fig. 10 is a detailed sectional view on an enlarged scale taken approximately on the line 10—10 of Fig. 1;

Fig. 11 is a detailed front elevational view of the mechanism of Fig. 10;

Fig. 12 is a detailed sectional view taken substantially on the line 12—12 of Fig. 11;

Fig. 13 is a detailed sectional view taken substantially on the line 13—13 of Fig. 1;

Fig. 14 is a sectional view on an enlarged scale, taken substantially on the line 14—14 of Fig. 1;

Fig. 15 is an elevational view as seen from the right of Fig. 14;

Fig. 16 is a view similar to Fig. 4, but with the parts in different positions relative thereto, showing one position of the parts during an operating cycle thereof;

Fig. 17 is a view similar to the lower portion of Fig. 16 on an enlarged scale with the parts in a further position during an operating cycle thereof;

Fig. 18 is a view similar to Fig. 17 but showing the parts in different positions relative thereto;

Fig. 19 is a view similar to Fig. 16 showing the parts in a further position during an operating cycle thereof;

Fig. 20 is a view similar to Figs. 17 and 18 but showing the parts in another position during an operating cycle thereof.

In the drawings and description, only the means and method necessary to a complete understanding of the invention are specifically set forth; further information as to the construction and operation of other related, usual and well known knitting machine elements, mechanisms, etc., may be found in one or more of the following publications:

1. Pamphlet entitled "Full-Fashioned Knitting Machines" published and copyrighted by the Tex-

tile Machine Works, Reading, Pennsylvania, in 1920.

2. Three catalogs entitled "The 'Reading' Full-Fashioned Knitting Machine Parts Catalog" published and copyrighted by the Textile Machine Works, in 1929, 1933 and 1940, respectively.

3. Booklet entitled "The 'Reading' High Production Full-Fashioned Knitting Machine" which, forming a supplement to the above noted 1940 parts catalog of the Textile Machine Works, is a publication of the Textile Machine Works, copyrighted by the latter in 1940.

4. Pamphlet entitled "Knitting Machine Lectures" published by the Wyomissing Polytechnic Institute, Wyomissing, Pennsylvania, in 1935.

The drawings show a portion of a machine to which the invention has been applied and which has a covering knife for each knitting section of the machine, the active edge of which moves toward and away from the fashioning points along a path entirely above the fabric so that there is no abrasive action on the fabric by said knife. This knife is adapted to be used at the center of a knitting section for preventing action of points in the narrow combs of a machine having both wide and narrow combs whenever it is desired or necessary to position the narrow combs at the centers of the knitting sections. Further, the knitting machine, of which a portion is shown herein, has covering knives adapted for use at the selvages of fabric made thereon, the center knives and the selavage knives being on separate shafts but operated from a common cam so that the shafts for both sets of knives turn through approximately the same angle although having a different action on the fabric.

Referring to the drawings more in detail, the machine shown will be understood to have a considerable number of knitting sections, probably thirty and in general is of known construction having a framework including transverse frames of which one known as a center frame is shown at 25 in Fig. 3, and longitudinal members tying said transverse frames together and including a center bed 29 and a front bed or table 27. A main cam shaft 30 is shown as mounted on the transverse frame members and cams (not shown) will be understood as fixed to shaft 30 to operate a needle bar 31 having knitting needles 32 thereon to cooperate with other knitting elements such as the sinkers and dividers, also operated from shaft 30, although indirectly. A sinker-head 33 is shown on the centerbed 29, having dividers 35 and sinkers 36 therein. The yarn to be knitted is laid on the noses of the sinkers and dividers which are then operated to press the yarn against the shanks of the needles to form loops to be knitted. At times, it is desired to fashion the fabric being knitted, that is, to narrow or widen it.

For this purpose, the machine is provided with a narrowing machine 40 including a back narrowing shaft 41 journaled on the transverse frames of the machine and connected to a front narrowing shaft 42 by arms, one of which appears at 43 in Fig. 3 so that shaft 42 can swing around shaft 41 as an axis. The arms 43 are fixed to the back narrowing shaft 41 by set screws or other suitable means and the front narrowing shaft is likewise suitably fixed to the arms 43 and has brackets 44 fixed to it in which are mounted narrowing rods 45, 46, 47 and 48. Narrowing rods 45 and 47 have fixed thereto narrow fashioning or transfer point combs 50 and 51, respectively, while rods 46 and 48 have wide

transfer point combs 52 and 53, respectively, fixed thereto, one narrow comb and one wide comb acting together at times on a given selvage with the wide combs being positioned at the ends of the needle bar 31 when not in use and the narrow combs being positioned at the middle of the needle bar when not in use, as shown in Fig. 1. The latter steps are of advantage in machines of a single unit type, that is, the machine is used to make both the leg and the foot of a stocking with the wide combs functioning to produce the leg, heel and foot narrowings, but to make the diamond point toe, both wide and narrow sets of combs for each knitting section are employed.

The weight of the front narrowing shaft 42 and parts supported therefrom is transmitted to the cam shaft 30 by means including a set of links one of which appears at 55 in Figs. 1 and 2. Each link 55 is pivotally connected to the shaft 42 at its upper end and pivotally connected at its lower end to one end of a lever 56, the other end of which is pivoted on a stud 61 on the center frame 25. As clearly shown in Figs. 1 and 2, the lever 56 is positioned above a circular disk 57 and a cam 58, carried on the shaft 30. Each lever 56 has a lug 62 near its rear end which projects from the under side of the lever and is adapted to engage a jack member 72, as hereinafter set forth, slidably carried by a lever 60 also pivoted on the stud 61 between the lever 56 and the cam shaft 30 to transfer the weight of the narrowing machine to the lower lever 60. From the lever 60, the weight of the narrowing machine is transmitted to the shaft 30 by means of a roller type cam follower 63, which is mounted in lever 60 to rotate on an axle 64 fixed in the lever parallel to shaft 30, and adapted to cooperate with either disk 57 or cam 58 as desired. During knitting cycles, the follower 63 engages with the circular disk 57 which has a diameter such that the points in the combs are held in inactive position above the needles. At the beginning of a fashioning cycle, the pattern means of the knitting machine shifts shaft 30 along its axis so that follower 63 engages the cam 58 to dip the points in the combs to engage certain of the loops on the needles and to transfer them to adjacent needles in the usual manner.

The narrowing machine of the usual full-fashioned knitting machine is provided not only with transfer point combs but with a picot or lace bar 65 which also acts to transfer loops from the needles on which they were formed to others. Picot bar 65, shown in Fig. 1, is carried by means of arms 67 on a shaft 66 also supported in the bracket 44 on the narrowing shaft 42. Shaft 66 can be turned so that the bar 65 is in inactive position, as shown in Fig. 1, or in a lowered position in which its points may act on loops on the knitting needles. In the lowered position, the picot bar is positioned below the combs 50-53 when the bar is to act on the loops, the picot bar 65, however, being recessed as shown at 70 to permit the fashioning points to overlap the picot bar to some extent, when the bar is to be used, and at 71 to clear a covering knife arrangement for the combs 50 and 51 and hereinafter set forth. In the present embodiment of the invention the picot points and the fashioning points when active must each be at the same level and the latter points at a higher level during operation of the picot points, the front narrowing shaft 42 operates at a higher level when the picot points are to act on the loops than when the fashion-

ing points are to so act. Therefore, a means is shown for varying the level of the front narrowing shaft 42 with respect to the axis of rotation of the follower 63 and such means is shown in Fig. 2 as comprising the jack member 72 which is slidably mounted on lever 60 to move parallel to the axis of shaft 30 beneath lug 62 to move a high portion 73 of the jack, beneath the lug 62 to hold the front narrowing shaft in position to permit the picot points to operate and to prevent the points in the combs 50 to 53 from engaging the needles. During a cycle when the points on the fashioning combs are to operate, the jack 72 is positioned, as shown in Fig. 2, so that the lug 15 62 is in engagement with a low point of jack member 72. For shifting jack 72 from one position to the other, a two part lever 74 is rotatably mounted on lever 60. The rear part of lever 74 engages jack 72 and the forward part of lever 74 20 extends between two collars 75 on a rod 76 which extends parallel to shaft 30 and also to jack 72. In order that the rod 76 may be shifted to move either the high portion 73 or the low portion of member 72 beneath the lug 62, to change from a 25 fashioning operation to a picot or lace operation, the narrowing machine must be raised to its highest inactive position by means not shown. Further details and operation of the foregoing mechanism for operating the narrowing machine at two different levels is more fully shown and 30 described in Held Patent No. 2,242,070.

As shown, a covering knife 80 is provided for each pair of small combs 50 and 51. Knives 80 are operated from a shaft 81 journalled in 35 brackets one of which is shown at 78 secured to one of the brackets 44 on the shaft 42 of the narrowing machine 40. As best shown in Figs. 4 and 5, the knife 80 is secured to the free end of a lever 79 as by screws 84 or other suitable means. The lever 79 is pivotally mounted between the arms 40 of the bifurcated portion of a lever 82 by means of a gudgeon 83 to which the lever 79 is secured, the lever 82 being secured to the shaft 81.

The shaft 81 is held in fixed angular position 45 during the majority of the period the knitting machine is in operation by coil springs 85, one of which is shown in Figs. 11 and 12, in cooperation with a disk 86 on shaft 30, shown in Fig. 3, together with intermediate members. Spring 85 is 50 connected at its lower end to a pin 87 fixed to the bracket 78 and at its upper end to the upper end of a link 88. The link 88 is provided with a slot 89 through which extends a shouldered portion of a stud 90 fixed to the bracket 78, the link being 55 movable in a predetermined path between a head portion 93 of the stud 90 and the bracket 78. The link 88 is pivoted at its lower end to a disk 91 fixed to and eccentrically mounted on shaft 81. In the position shown in Figs. 4, 5 and 12, 60 the knife 80 and shaft 81 are in active positions with the spring 85 tending to turn the shaft 81 in the clockwise direction as viewed in Fig. 12. In order to throw knife 80 out of action, the shaft 81 is turned counterclockwise as viewed in Fig. 12 65 to move the connection between the disk 91 and link 88 to the left of the shaft 81 with the spring 85 tending to maintain the link in said position.

To control the action of shaft 81 and knife 80 when in active position, means is provided 70 including a lever 95 shown in Figs. 1, 6 and 7 which is loosely carried on the shaft 81. The lever 95 is held in engagement with a vertically movable shelf-like member 96 by means of a clutch member 118 secured to the shaft 81. The clutch member has a projection 119 which ex-

tends into the path of a tooth-like projection 120 on the lever 95, shown in Fig. 9, the spring 85 acting through the clutch member 118 to press a rounded free end of lever 95 against the member 96. The member 96 is fixed to a vertically movable rod 97 by means of set screws 98, shown in Figs. 6 and 7, the rod 97 being connected at its lower end to a stud 102 pivotally carried at one end of a lever 99, shown in Figs. 1 and 3, and the other end of said rod passing through an opening in a pin 103 pivotally carried in an arm 101 on one of the brackets 78, Fig. 3. Lever 99 is pivotally mounted on the framework of the machine and has a transverse bolt or pin 100 therein on which is rotatably mounted a roller type cam follower 105. The parts are so positioned that, during knitting cycles, follower 105 rests on circular disk 36 as shown in Fig. 3. The shelf member 96 is thereby held at such a level that the lever 82 on shaft 81 is held in the angular position shown in Figs. 4 and 5. At the same time, the cam shaft 38 is in its knitting or left hand position as viewed from the front of the machine, Fig. 1, and the fashioning points are in inactive position above the highest level reached by the needles, as shown in Fig. 3. With this arrangement, when the knife 80 is in active position, as shown in the drawings, the projection 119 of member 118 is in engagement with the projection 120 on the arm 95 and knife 80 will follow the movements of the arm 95 as controlled by the rod 97. When, however, for any reason, the shaft 81 and projection 119 is moved in the counterclockwise direction, as viewed in Fig. 9, to move the knife 80 to inactive position, the arm 95 will have no effect on the shaft 81.

The movement of the shaft 81 in the counterclockwise direction is limited by a pin 123 projecting from an eccentric collar 124, as shown in Figs. 14 and 15, fixed to the shaft 81, the pin engaging a recess 125 in one of the brackets 78. When the narrowing machine is raised to shift the member 72, the shaft 81 is raised with the shaft 42 which permits the lever 95 to loosely turn in a clockwise direction on the shaft 81. To prevent the lever from turning beyond a position in which it will be contacted by the member 96 when the narrowing machine is again lowered into active position, the lever 95 is provided with an arm 115 adapted to engage the shaft 63 to limit the clockwise movement of the arm 95.

When a fashioning or a lace operation is to be performed, means controlled by the pattern chain (not shown) of the knitting machine causes shaft 38 to be shifted to the right to move the disk 57 from alignment with the cam follower 63 on which the front narrowing shaft 42 is supported and move the cam 58 into alignment with said follower to lower the narrowing machine, and thereby the parts supported from the front narrowing shaft 42, and also causes the disk 36 to be moved from alignment with the follower 105 and a cam 106 to be moved into alignment with said follower. The cam for dipping the front narrowing shaft lowers and raises the fashioning points in the combs in the usual manner and cam 106 acts to lower rod 97 to cause knife 80 to move between the points on the narrow combs 59 and 51 and the needles 32 to prevent the points from acting on loops on the needles within the span of the narrow combs. In cooperation with the action of the cam 106 on rod 97 to cause knife 80 to coact with the fashioning points, the lever 79 of the knife structure has parallel ribs 108 pro-

jecting therefrom for engagement with a shaft 110, the ribs 108 being held against the shaft 110 by a spring 109. The spring 109 is positioned between the ribs 108 and is connected to the levers 82 and 79, as shown in Fig. 5, to maintain the edges of the ribs in contact with shaft 110 to cause the knife 80 to follow the necessary path to prevent the points on combs 59 and 51 from engaging the loops on the needles during fashioning cycles of the knitting machine.

At the beginning of a fashioning cycle, knife 80 is positioned as shown in Figs. 4 and 5, follower 105 being on the high part of cam 106 and follower 63 being on the high point of the cam 58 for dipping the front narrowing shaft, both such high points having a predetermined angular position with relation to cam shaft 38. As the followers 63 and 105 pass off the high points of their cams, the narrow combs 59 and 51 being assumed to be laid out at the center of the knitting section and wide combs 52 and 53 being positioned to act on the selvages of the fabric, the points of the wide and narrow combs move downwardly from the position, shown in Figs. 4 and 5, toward the needles while knives 80 move downwardly and into engagement with the points, as shown in Fig. 16, in the narrow combs at a level above the tops of the needles and prior to movement of the needles into engagement with the points. An adjustable stop bolt 111 is fixed in an arm 107 integral with lever 82 and is adapted to contact shaft 110 when the shaft 81 is in the angular position shown in Fig. 16 to predetermine the pressure between knife 80 and the points in combs 59 and 51. As the points and knife 80 continue to move downwardly with the needles, the needles are also moved toward the points in the usual manner until the upper parts of the needle beards contact the knife with the result that the needles are bent in a direction away from the points from their normal position and the beards of the needles are opened slightly, as shown in Fig. 17. The points, knife and needles then continue downwardly together until the tip of the needle beard passes the loops held on the needles, the knife preventing the points from engaging the loop on the needle, as shown in Fig. 18. The points not contacted by the knife 80 close the beards of the needles aligned therewith and pass between the loops and the needles preparatory to lifting the loops from the needles, a result occurring when the needles then pass below the upper edges of the knock-over-bits. The points and needles then rise continuously to the relative positions shown in Fig. 19 along a flat or somewhat straight path. At this position in the cycle, the points being a little above the knockover-bits, the points of the combs which have not been laid out are shifted by their rods one or two needle spaces to bring the points into vertical planes, transverse to the needle bars, of other needles than those from which the loops were lifted. As the points are moved to the position shown in Fig. 19, a high portion 104 of the cam 106 also raises the member 96 to turn shaft 81 from its angular position in Fig. 16 to that in Fig. 19 to cause the knife 80 to move upwardly and forwardly away from the points along a path well above the fabric at all times. After the active points have shifted the engaged loops to adjacent needles, the points and needles go down together to the relative positions shown in Fig. 20, at which point in the cycle the sinkers are brought forward above the fabric. It is to be understood that when the points of the combs 59

and 51 are in inactive position at the center of the knitting section they receive no movement corresponding to the usual loop shifting movement but remain in alignment with the same needles throughout their inactivity. The cam 106 is so formed that the shaft 81 and arm 82 hold the knife 80 in substantially the same position relative to the points as the narrowing machine moves down to carry the points from the position shown in Fig. 19 to that shown in Fig. 20, the cam having a relatively low portion immediately following the portion 104 which compensates so far as the angle of shaft 81 is concerned for the downward movement of the narrowing machine. Following the positions shown in Fig. 20, the parts return to the positions of Figs. 4 and 5. It will be seen, therefore, that the path of knife 80 is such that it is entirely free of contact with the fabric and the sinkers and contacts the points and needles only to prevent the points from engaging the loops on the needles.

Also operated by rod 97 from cam 106 are knives 130, arranged two for each knitting section to act on certain of the points in the wide combs used to operate on the selvage portions of heel sections of blanks for single unit stockings. As knives 130 act on portions of the fabric which are reinforced, it is not necessary to vary their arrangement and operation as compared to those previously used in making diamond point toes except to locate them outwardly from the center of the knitting sections. The knives 130 are mounted on arms 129 secured to the shaft 110. Shaft 110 is shown as having an eccentric collar or disk 132 analogous to the eccentric disk 91 on shaft 81. Disk 132 is pivotally connected to the lower end of a link 133, having a slot 134 which embraces a bolt 131 at the opposite side of bracket 78 from link 88 for shaft 81. The upper end of link 133 is connected to a throw-over spring 135 the lower end of which is connected to a pin 128 carried in the bracket 78. Contrary to the showing of spring 85 in Fig. 12, however, spring 135 is shown in Fig. 10 as thrown over to the position in which the spring holds knives 130 in their inactive positions. When it is desired to move the covering knives 130 from their inactive position, shown in Fig. 13, to their active position, the disk 132 is rotated in a clockwise direction, as viewed in Fig. 10, to carry the point of connection of the lower end of link 133 from the left to the right of the center of shaft 110, to a point analogous to that shown in Fig. 12 for the point of connection between link 88 and disk 91. A lever 136, shown in Figs. 6 and 8, is loosely carried on shaft 110 corresponding generally to lever 95 on shaft 81. The lever 136 is pressed by the spring 135 against a shelf member 137, fixed to the rod 97, by means of a clutch member 145 secured to the shaft 110. The clutch member 145 has a projection 146 which is adapted to engage a projection 147 on the lever 136 when the knives 130 are in the lowered or active position (not shown). When the knives 130 are in the raised or inactive position shown in Fig. 13, the projection 146 on collar 145 is in the position shown in Fig. 8, in which position the action of the spring is not transmitted to the lever 136. Limits are set to the movement of shaft 110 and knives 130 in both directions. To this end, shaft 110 has an eccentric collar 138 fixed thereon alongside bracket 78, as shown in Figs. 14 and 15, and on the opposite side thereof from collar 124. Collar 138 has a bolt 140 fixed therein one end of which is adapted to contact the bottom of a

recess similar to the recess 125 in the front face of bracket 78, to limit the movement of shaft 110 in the counterclockwise direction as viewed in Fig. 13, thereby holding knives 130 in the inactive position. To prevent the spring 135 from exerting excessive pressure on the points of the wide combs 52 and 53 when the knives are moved to active position, the shaft 110 has an arm 141 adjustably mounted thereon which is adapted to engage the shaft 81 to limit the movement of the knives 130 in the clockwise direction toward the points, as viewed in Fig. 13. Further, the lever 136 is provided with an arm 142 adapted to engage the shaft 81 to prevent the end of lever 136 from turning in a clockwise direction, as viewed in Fig. 8, beyond the vertical path of the member 137 when the narrowing machine 40 is raised to shift the jack 72, as hereinbefore set forth, while the knives 130 are in the lowered or active position on the narrowing machine.

In operation, the knives 130 follow the same path as in the usual covering motion shown in the hereinbefore referred to "Reading" parts catalogs, that is, the knives are lowered with the fashioning points to prevent the points covered by the knives from engaging loops on the needles. The knives are then moved away from the points along an arcuate path about the axis of the shaft 110, which path carries the knives below the level of the fabric being knitted. However, as this path of movement in the present arrangement is close to the selvage edges of the reinforced portions of the fabric no damage occurs due to the knives striking the fabric.

In the operation of the knife 80 during fashioning operations, the cam 106 operates the shaft 81 through the rod 97, member 96 and lever 95 to prevent the points of the narrow combs 50 and 51 from engaging loops on the needles 32. As the narrowing machine 40 is lowered by the cam 58, the cam 106 also lowers the rod 97 and member 96 whereupon the spring 85 exerts pressure to turn the shaft in the clockwise direction and, through engagement of the projection 119 on the member 118 with the projection 120 on the lever 95, maintains the lever 95 in contact with the member 96 as it is lowered. With the turning movement of the shaft 81 and the guiding of the ribs 108 of the lever 79 against the shaft 110, the knife is moved downwardly and into engagement with the points from the position shown in Figs. 4 and 5 to the position shown in Fig. 16. As the points and knife continue to move downwardly as shown in Fig. 17 whereupon the points, knife and needles continue to move downwardly together until the tips of the needle beards pass the loops held on the needles and into the knockover-bits as shown in Fig. 18. The knife continues to move downwardly with the points and needles until it reaches a point close to the tops of the knockover-bits and is then moved upwardly and away from the points by the cam 106 to the position shown in Fig. 19, the knife and points remaining in this relation until again raised to the position of Fig. 4.

The covering knife 80 prevents the points of the narrow combs 50 and 51 from engaging loops on the needles during all fashioning operations to the start of the toe portion of the stocking fabric where the narrow combs 50 and 51 are moved outwardly to coact with the wide combs 53 and 52 respectively in forming the toe narrowings. Near the end of the toe narrowings the knife 80 again operates to progressively prevent the points of

the narrow combs from engaging the loops in forming the diamond point portions of the toe narrowings.

Of course, the improvements specifically shown and described by which is obtained the above results can be changed and modified in various ways without departing from the invention herein disclosed and hereinafter claimed.

I claim as my invention:

1. A covering knife arrangement coacting with the needles and points of a full-fashioned knitting machine and comprising a shaft, an arm on said shaft, a second arm pivoted to said arm and having a knife thereon, a guide member, a cam surface on said second arm cooperating with said member to determine the path of the active edge of said knife, means for holding said cam surface against said guide member when the knife is to be used, said cam surface inclining rearwardly and downwardly, and means turning said first arm to carry the pivot of said second arm downwardly and rearwardly to contact the active edge of the knife with the points and afterward turning it upwardly and forwardly to withdraw the active edge of the knife from the points along a path preventing contact of the knife edge with the fabric.

2. In a full-fashioned knitting machine having knitting needles and fashioning points, the combination of a covering knife placed centrally of a knitting section, a covering knife placed to act on the fashioning points and the needles at a selvage of a heel portion of a blank made on the section, both said knives having active and rest positions, actuating means common to both said knives, and connections between said knives and actuating means constructed and arranged to give said central knife a relatively quick upward movement compared to said selvage knife.

3. In a full-fashioned knitting machine, a narrowing machine mechanism, two shafts on said mechanism, a covering knife on each of said shafts, one of said shafts assisting in guiding the knife on the other shaft in the approach and retreat of the knife to and from its effective position, both said knives having active and inactive positions, and actuating means common to both said knives.

4. In a full-fashioned knitting machine, a covering knife, a shaft, an arm fixed to said shaft on which said knife is pivoted, transfer points, knitting needles with which said points cooperate in a fashioning cycle, a guide fixed relatively to said shaft and a member fixed to said knife and having a surface cooperating with said guide to cause the knife to withdraw from the points along a path upwardly inclined away from the points.

5. In a full-fashioned knitting machine, a knitting section provided with a narrowing machine having fashioning points as well as center and selvage knives mounted thereon, and separate oscillatable shafts for said center and selvage knives, one of said knives being fixed to turn with its shaft and the other being pivotally supported from its shaft and arranged and guided to withdraw from the points along a path entirely above the fabric formed on the section.

6. In a full-fashioned knitting machine, a knitting section provided with a narrowing machine having fashioning points as well as center and selvage knives mounted thereon, separate oscillatable shafts for the center and the selvage knives, one of said knives fixed to its shaft to turn therewith, and the other pivotally supported

from its shaft and arranged and guided to withdraw from said points along a path entirely above the fabric formed on said section, and common actuating means for the shafts of said knives.

7. In a full-fashioned knitting machine, fashioning points having a down and up movement in fashioning cycles of the machine, a covering knife, a shaft for said knife having an arm fixed thereto on which said knife is pivotally mounted, means oscillating said shaft to cause said knife to approach and retreat from said points, and guiding means for said knife providing coacting rounded and approximately plane surfaces causing said knife to approach said points along a downwardly inclined path whose lowest point is above the fabric and to withdraw from the points upwardly along said path.

8. In a full-fashioned knitting machine, a knitting section including a narrowing machine having fashioning points carrying out a down and up movement in fashioning cycles of the machine, knitting needles, two covering knives mounted on said narrowing machine, shafts for said knives, one knife being fixed to its shaft to turn through the same arc as the shaft and the other shaft having an arm fixed thereto on which the other knife is pivoted, said other knife having a part providing an approximately plane surface, and a spring arranged to draw said surface against the shaft for the one knife, the other knife approaching and withdrawing from said points in a path entirely above the fabric knitted by said needles, due to the coaction of said surface and said shaft for the one knife.

9. In a full-fashioned knitting machine, a front narrowing shaft arranged for an up and down movement about an axis at the rear of the shaft and having point combs thereon, a covering knife for each knitting section of the machine placed centrally of the section and having a motion withdrawing from the points inclining upwardly and forwardly therefrom to entirely avoid contact with fabric made on the section, knives for each section placed outwardly from the center thereof and having a circular motion withdrawing from the points, and means including a cam common to both the central and outwardly placed knives for operating them.

10. In a full-fashioned knitting machine, a covering knife adapted to cooperate with fashioning points and needles to prevent the points from affecting loops on the needles and means operating said knife to cause it to approach its position of cooperation with the points and needles and to withdraw therefrom along a path inclined upwardly from its cooperating position with respect to said points and needles.

11. In a full-fashioned knitting machine, a covering knife, a shaft for operating said knife, an arm fixed to said shaft on which said knife is pivotally mounted, means oscillating said shaft to cause said knife to approach and retract from an active position, and stop means for preventing the knife from overrunning its desired active position.

12. In a full-fashioned knitting machine, a comb having fashioning points therein, a covering knife for engaging said points, a shaft for operating said knife, an arm fixed to said shaft on which said knife is pivotally mounted, means for oscillating said shaft, a guide member coacting with said means to cause said knife to approach said points along a downwardly inclined path to engage them, and a stop member fixed with relation to said knife and contacting said

guide member to determine the end of said approaching movement.

13. In a full-fashioned knitting machine, a comb having fashioning points therein, a covering knife for engaging said points, a shaft for said knife, an arm fixed to said shaft on which said knife is pivotally mounted, means for oscillating said shaft, a guide member coacting with said means to cause said knife to approach said points along a downwardly inclined path to engage them, and a stop member adjustably fixed with relation to said guide member to determine the relative positions of said knife and points when in engagement.

14. In a full-fashioned knitting machine, a comb having fashioning points therein, a covering knife adapted to engage said points at desired times, a shaft for said knife, an arm fixed to said shaft on which said knife is pivotally mounted, means for oscillating said shaft, a guide member, a member having a straight guide surface and arranged to move with said knife and coacting with said guide member to cause said knife to approach said points along a downwardly inclined path, and a stop member adjustably fixed with relation to said guide member to determine the relative positions of said knife and points for engagement.

15. In a full-fashioned knitting machine, two shafts and a covering knife on each of said shafts, one of said shafts assisting in guiding the knife on the other shaft in the operative movements of the latter knife, throw-over spring means, one for each of said knives, and stop means for each knife for limiting its movements in response to said spring means.

16. In a full-fashioned knitting machine having knitting needles and fashioning points, the combination of, two shafts and a covering knife on each of said shafts, one placed centrally of a knitting section and one placed to act on the needles and points at the selvage of a heel portion of a blank made on the section, both said knives having active and rest positions, actuating means common to both said knives, throw-over spring means, one for each of said knives, for biasing the knives toward one end or the other of their paths, and stop means for limiting the movements of said knives in response to said spring means.

17. In a full-fashioned knitting machine, a knitting section provided with narrowing mechanism having fashioning points as well as center and selvage knives mounted thereon, separate oscillatable shafts for the center and the selvage knives, a supporting bracket common to said shafts, one of said knives being fixed to its shaft to turn through the same angle as the shaft and the other being pivotally supported from its shaft and arranged and guided to withdraw from said points along a path entirely above the fabric formed on said section, throw-over spring means, one for each of said shafts, common actuating means for said shafts, and stop means one for each knife and each stop means including said bracket.

18. In the method of operating a full-fashioned knitting machine including needles, point fashioning instrumentalities and covering knives, the steps which comprise operating the knives along a downwardly inclined path in timed relation with the loop transfer during fashioning to cover certain numbers of the needles to prevent transfer of the loops being formed on said covered needles, and then moving said knives from operative relation with said needles and points along

a path entirely above and out of contact with the fabric formed on said needles.

19. In a full-fashioned knitting machine having knitting needles and fashioning points, a covering knife placed centrally of a knitting section, a covering knife placed to act on the needles and points at a selvage of a portion of a blank made on the section, both said knives having active and rest positions, and actuating means for both said knives, and means acting on one of said knives when in its active position to cause it to move away from said points in a line of movement distinct from the line of the movement of said other knife.

20. In a full-fashioned knitting machine, two independently movable knives, separate mountings for each of said knives, means associated with one of said mountings for guiding the knife carried by the other mounting in its approach to its effective position and actuating means for said knives.

21. A covering knife arrangement coacting with the needles and points of a full-fashioned knitting machine and comprising a shaft, an arm on said shaft, a second arm pivoted to said arm and having a knife thereon, a guide member, a surface on said second arm cooperating with said member to determine the path of the active edge of said knife, means for holding said surface against said guide member when the knife is to be used, and means for turning said shaft to move said surface relative to said guide member.

22. In a full-fashioned knitting machine the combination of a covering knife arrangement comprising, a shaft, an arm fixed thereon, a second arm pivoted to said first arm, and a covering knife carried by said second arm, and means operating said arms whereby compound movements may be imparted to said knife.

23. In a full-fashioned knitting machine having needles, a narrowing machine, points on the narrowing machine, means for actuating the narrowing machine to move said points into and out of cooperative relation with said needles in a narrowing cycle, a covering knife on said narrowing machine and means cooperating with said knife and narrowing machine to cause said knife to approach along a downwardly inclined path and contact said points and needles during the narrowing cycle, and said means causing said knife to withdraw from the points along said inclined path upwardly and away from said points.

24. A covering knife mechanism arranged for coaction with the needles and points of a full-fashioned knitting machine and comprising a shaft, a lever on said shaft, an arm pivoted to said lever and having a knife thereon, a guide member, a surface on said arm cooperating with said member to guide said knife along a path inclined downwardly toward said points for said coaction with said needles and points, and means for turning said shaft to move said surface relative to said guide member.

25. In a full-fashioned knitting machine, a knitting section provided with a narrowing machine having fashioning points as well as center and selvage knives mounted thereon, separate oscillatable shafts for the center and selvage knives, and means for operating said shaft, one of said knives being fixed to its shaft to turn through the same angle as the shaft and the other being pivotally supported from its shaft and arranged and guided to withdraw from said

points along a path entirely above the fabric formed on said section.

26. In a full-fashioned knitting machine, a knitting section provided with a narrowing machine having fashioning points as well as center and selvage knives mounted thereon, separate oscillatable shafts for the center and selvage knives, one of said knives being fixed to its shaft to turn through the same angle as the shaft and the other being pivotally supported from its shaft and arranged and guided to withdraw from said points along a path entirely above the fabric formed on said section, and actuating means for the shafts of said knives.

27. In a full-fashioned knitting machine, fashioning points having a down and up movement in fashioning cycles of the machine, a covering knife, a shaft for said knife having an arm fixed thereto on which said knife is pivotally mounted, means for operating said shaft, and coacting means on said shaft and knife operating to cause said knife to approach said fashioning points along a downwardly inclined path whose lowest point is above the fabric and to withdraw from the points upwardly along said path.

28. In a multi-section full-fashioned knitting machine, a front narrowing shaft arranged for an up and down movement and having fashioning points thereon, a covering knife for each knitting section of the machine placed centrally of the section, guide means defining a path for said knife entirely above the fabric in each section, selvage knives for each section operable to withdraw from contact with said points, and means for operating said knives.

29. In a full-fashioned knitting machine, a knitting section provided with narrowing mechanism having fashioning points as well as center and selvage knives mounted thereon, separate oscillatable shafts for the center and the selvage knives, a supporting bracket common to said shafts, one of said knives being fixed to its shaft to turn through the same angle as the shaft and the other being pivotally supported from its shaft and arranged and guided to withdraw from said points along a path entirely above the fabric formed on said section, and common means to actuate said knives along the path individual thereto.

30. In a full-fashioned knitting machine, the combination of knitting needles, fashioning points, a covering knife for said points, a frame on which said knife and points are carried,

means holding said frame during knitting cycles so that the active edge of said knife is forward of the points and above their lower ends, means giving said frame two downward movements during fashioning cycles to bring the points, except those under the action of the knife, into contact with the needles, means for actuating said knife downwardly and upwardly on the frame within the period of a fashioning cycle, and means guiding said knife positively, downwardly and rearwardly relative to the points, to press the knife between the points and the needles and guiding the knife upwardly and forwardly relative to the points and needles, said actuating means being constructed and arranged to act in conjunction with said guiding means to maintain the knife out of contact with the fabric formed on the needles from the time the knife first separates from the points and the needles until the end of the cycle.

31. In a full-fashioned knitting machine, two shafts and a covering knife on each of said shafts, means for operating said knives, and means for guiding one of said knives in its operative movement including the shaft for the other of said knives.

32. In a full-fashioned knitting machine, a narrowing machine, two shafts on said narrowing machine, a covering knife fixed to one of said shafts, a covering knife pivoted to the other of said shafts, means for operating both of said knives along different predetermined active paths, and means carried on said narrowing machine for guiding said pivoted knife in its active path.
